MACHINE FOR SIZING BUSHINGS

John Haller, Northville, Mich.

Application April 25, 1947, Serial No. 743,875

8 Claims. (Cl. 78—18)

1

This invention relates to fluid-operated presses and in particular to presses for shaping articles to their proper sizes.

One object of this invention is to provide a sizing press to overcome dimensional variations arising in the manufacture of bushings prepared by powder metallurgy so as to bring the bushings to their intended dimensions after they have been subjected to the sintering operation.

Another object is to provide a sizing press for bushings prepared by powder metallurgy, as set forth in the preceding object, wherein the various elements of the press operate automatically in timed relationship to carry out the various steps in the bushing sizing cycle of operations.

Another object is to provide a sizing press for bushings prepared by powder metallurgy, as set forth in the preceding objects, wherein the motions of the various elements of the press are started and stopped according to a predetermined sequence of operations by means of limit switches and a pressure-operated switch, so that the machine is substantially automatic in its operation after it has once been started.

Another object is to provide a sizing press for bushings prepared by powder metallurgy, as set forth in the preceding objects, wherein the bushings are fed automatically to the press, forced automatically into a sizing die, sized for their internal and external dimensions, and automatically ejected from the die, after which the various elements of the press are then returned automatically to their start positions preparatory to carrying out a new sizing operation upon the next bushing.

In the drawings:

Figure 1 is a central vertical section, partly in side elevation, through a fluid pressure press for sizing bushings, together with the electric and hydraulic circuits therefor according to a preferred form of the invention;

Figure 2 is a central longitudinal section through one of the four-way valves used in the hydraulic circuit shown in Figure 1;

Figure 3 is a vertical cross-section taken along the line 3—3 in Figure 1, showing the bushing-feeding chute and sizing die;

Figure 4 is a diagrammatic longitudinal section through the principal working elements of the press of Figure 1 in their starting position;

Figure 5 is a longitudinal section similar to Figure 4, but showing the positions of the parts after the abutment plunger has moved into engagement with the sizing die;

Figure 6 is a longitudinal section, similar to

2

Figures 4 and 5, but showing the positions of the parts after the bushing has been forced into the sizing die to properly size the outer dimension thereof;

5 Figure 7 is a view similar to Figures 4, 5 and 6, but showing the positions of the parts after the internal sizing plunger has been moved through the bushing to properly size the internal bore thereof;

10 Figure 8 is a view similar to Figures 4 to 7 inclusive, but showing the positions of the parts after the abutment plunger has been retracted and the bushing pushed out of the sizing die; and

15 Figure 9 is a view similar to Figures 4 to 8 inclusive, but showing the positions of the parts after the internal sizing plunger has been retracted and the finished bushing is being ejected.

Hitherto, the making of bushings by powder metallurgy has been subject to considerable difficulty because of the great deviations from their intended dimensions during manufacture. Even though the formation of the bushings is very carefully controlled, after the sintering operation has been carried out, such bushings are frequently found to deviate very widely from their desired dimensions. In order to use such bushings properly for bearing purposes, it is, of course, necessary that they should very accurately fit the shafts which they are used to support and at the same time provide very accurate clearances. The purpose of the present machine is to restore such bushings to their proper dimensions, since these bushings by reason of their material and peculiarities of construction are capable of deformation into their proper dimensions.

Mechanical construction of press

Referring to the drawings in detail, Figure 1 shows diagrammatically a bushing sizing press, generally designated 10, in longitudinal vertical section, together with the hydraulic circuit for the various valves which control the motions of the plungers. The sizing press 10 consists of a base or bed 11 having a die holder 12 bolted thereto as at 13 and having stepped bores 14, 15 and 16 therein for receiving a tubular die 17. The die 17 has an internal bore 18 which is of precisely the desired outside diameter for the finished bushings. The die 17 is held in position within the bore 15 by a retaining ring 19 secured thereto as at 20, and fitting into an annular external recess 21 in the die 18.

The bushings 22 to be sized by the press of the present invention are, as previously stated, made by powder metallurgy and, after sintering, are

placed in an inclined feed chute 23 (Figure 3) mounted on a bracket 24 secured as at 25 to the die holder 12. The chute 23 is provided with a floor 26 which is extended downward below the lower end 27 of the chute and terminates in a 5 curved rest 28 which has a flared forward edge 29.

Likewise mounted on the base or bed 11 and bolted thereto as at 31 is an abutment cylinder 32 having a bore 33 in which is reciprocably mounted a plunger 34 having a head 35 (Figure 1). The plunger 34 passes through a bore 36 in the end wall of the cylinder 32 and carries on its outer end an enlargement 37 with a socket 38 therein. Mounted in the socket 38 and secured to the enlargement 37 by the bolt 39 is an annular abutment 40 having a tubular recess 41 therein and an annular abutment portion 42 thereon.

The cylinder 32 in its side wall is provided with spaced fluid ports 43 and 44 which are hydraulically connected, as set forth below. A cylinder head 45 is bolted as at 46 to the abutment cylinder 32.

Mounted on the base or bed 11 on the opposite side of the die holder 12 from the abutment cylinder 32 and bolted thereto as at 47, is a sizing cylinder 48. The sizing cylinder 48 is provided with a bore 49 within which a hollow outer plunger 50 reciprocates, access to the cylinder bore 49 being provided by ports 51 and 52 (Figure 1) connected to the hydraulic system as described below. The outer cylinder 48 is closed at its outer end by a cylinder head 53 bolted thereto as at 54 and containing the central axial bore 55. Similarly, the opposite end wall of the cylinder 48 is provided with an axial bore 56.

The plunger 50 is provided with a hollow head 57 having an annular recess 58 in one end wall thereof into which the enlarged end of the hollow plunger rod 59 snugly fits and is held in position by a retaining ring 60 bolted as at 61 to the head 57. The hollow rod 50 in turn is provided with an annular recess 62 in which is secured the enlarged end of an outer sizing plunger 63 of tubular form, and held in position by a retaining ring 64 bolted thereto as at 65. The outer sizing plunger 63 is provided with an annular abutment face or end 66 of approximately the same size as the ends of the bushings 22 to be sized. The provision of the recess 62 and retaining ring 64 enables the outer sizing plunger 63 to be removed and other plungers of different sizes inserted, according to the different sizes of bushings 22 to be sized.

The outer sizing plunger 63 is provided with a longitudinal bore 67 (Figure 1) of substantially the same size as the inner bore of the bushing 22 to be sized and containing an inner sizing plunger 68 of the same outer diameter as the inner diameter intended for the bushings 22. The plunger 68 passes through a bore 69 in the end of the hollow plunger rod 59 and is seated in a recess 70 in the end of a screw plug 71, to which it is secured by a fastener 72 threaded into the end thereof. The screw plug 71 in turn is threaded into a recess 73 in the end of an inner plunger 74 which is reciprocably mounted in the bore 75 within the hollow plunger rod 59 and which is provided with a head 76 which is in turn reciprocable in the enlarged bore 77 within the hollow head 57.

The head 76 and plunger 74 are provided with an axial bore 78 and a passageway 79 leading therefrom (Figure 1) to the bore 77. Mounted in the bore 78 is a tubular stem 80 having a lon-

gitudinal passageway 81 leading therethrough to a port 82. The stem 80 is provided with a thread enlargement 83 which is threaded into the outer end of a hollow plunger 84. The inner end of the plunger 84 is enlarged as at 85 and is threaded into the outer end of the bore 77 so as to form a closure therefor. The hollow plungers 84 and 59 reciprocate to and fro within the bores 55 and 56 respectively. The annular passageway 86 within the hollow plunger 84 and outside the tubular stem 80 leads to a port 87 (Figure 1).

Hydraulic system

In order to reciprocate the various plungers, the cylinders containing these plungers are connected to three conventional solenoidally operated four-way valves, generally designated 88, 89 and 90 respectively. Each of these valves is of any suitable type, and may consist of the type shown for purposes of illustration in Figure 2. The valve 88, for example, may consist of a valve casing 91 (Figure 2) containing a longitudinal bore 92 with annular enlargements 93 and 94 near the opposite ends thereof and interconnected by a passageway 95 in the wall thereof. The passageway 95 terminates in an exhaust port 97 leading to a fluid supply tank, as described below. Diametrically opposite the exhaust port 97 is a pressure fluid supply port 96. On either side of the pressure fluid supply port 96 are ports 98 and 99 which are customarily piped to the opposite ends of the cylinder containing a plunger which it is desired to reciprocate in opposite directions. These ports 98, 99 alternately serve as pressure and suction ports respectively as the plunger is reciprocated in opposite directions.

Reciprocably mounted in the bore 92 is a valve spool 100 having three spaced heads 101, 102 and 103 separated by neck portions 104 and 105. The valve spool 100 is also provided with a longitudinal passageway 106 having transverse central and end passageways 107. The valve spool 100 is connected at its opposite ends to operating rods 108 and 109 around which are coiled compression springs 110 adapted to urge the valve spool 100 into its neutral position (Figure 2) when neither of the rods 108 or 109 is pushed or pulled.

The operation of the conventional four-way valve shown in Figure 2 depends on the setting of the valve spool 100 as determined by the operating rods 108 or 109. These are sometimes operated manually, but in the present circuit are preferably operated by solenoids, as described in connection with the electrical circuit. When the valve spool is shifted to the left, pressure fluid passes from the port 96 into the port 98 and thence to the cylinder to be operated. Meanwhile, the fluid discharged from the opposite end of that cylinder passes through the port 99 and passageways 107, 106 and 95 out through the discharge port 97 to the tank.

When the spool 100 is shifted toward the right-hand end of the bore 92 (Figure 2) the reverse distribution of fluid occurs. Under these circumstances, pressure fluid is supplied from the port 96 through the neck portion 105 into the port 99 and thence to the cylinder being operated. The fluid displaced by the plunger thereof returns through the port 98 the passageways 107, 106 and 95 and the port 97 and returns to the fluid supply tank.

The ports 43 and 44 of the abutment cylinder 32 are connected by conduits 110 and 111 to the four-way valve 88, whereas the ports 51 and 52

of the outer bore 49 of the sizing cylinder 48 are connected by conduits 112 and 113 to the four-way valve 88 (Figure 1). The ports 82 and 87 connected to the hollow plungers or stem passageways 81 and 86 respectively are connected by conduits 114 and 115 to the four-way valve 90. The conduits just described are connected to ports in the four-way valves 88, 89 and 90 corresponding to the ports 99 and 98 in Figure 2. The pressure fluid for actuating the machine is supplied by a hydraulic pump 116, the pressure side or outlet of which is connected by the conduit 117 to the ports in the four-way valves 88, 89 and 90 corresponding to the ports 96 in Figure 2. The suction port of the pump 116 is connected by a conduit 118 to the fluid tank 119 upon which the pump 116 is conveniently mounted. An electric motor 120 coupled to the drive shaft 121 of the pump 116 operates the latter. The discharge ports of the four-way valves 88, 89 and 90 corresponding to the port 97 of Figure 2 are connected to the conduit 122 leading back to the fluid tank 119. The latter is filled with a suitable operating fluid, such as oil or water. The conduit 115 is connected by a branch conduit 123 to a pressure-responsive switch, generally designated 124 the discharge of which is connected by the conduit 125 to the conduit 122.

Electrical control system

In order to actuate the four-way valves 88, 89 and 90, each of these is provided with solenoid windings. The four-way valve 88 has solenoid windings 126 and 127 (Figure 1) adapted to shift solenoid armatures 128 and 129 on the ends of the control rods 108 and 109 respectively (Figure 2). Similarly, the four-way valve 89 is provided with solenoid windings 130 and 131 adapted to actuate the control rod armatures 132 and 133 and the four-way valve 90 has solenoid windings 134 and 135 operating the control rod armatures 136 and 137. The solenoid windings are controlled by a manual switch 140, limit switches 141, 142, 143 and 144, and by the pressure switch 124, as described hereinafter in connection with the operation of the invention. The limit switches 141, 142, 143 and 144 are supported respectively on brackets 145, 146, 147 and 148 mounted respectively upon the cylinder 32, die holder 12 and cylinder 48. The limit switch 141 is tripped by a projection 149 upon an arm 150 mounted upon an upright 151 which in turn is mounted upon the enlargement 37 of the plunger 34. The arm 150 also has an end portion 153 which actuates the limit switch 142. The limit switches 143 and 144 are actuated by a projection 153 and an end portion 154 on an arm 155 supported by an upright 156 mounted upon the hollow plunger rod 59.

The limit switches 141 and 142 are single-throw normally open switches whereas the limit switches 143 and 144 are double-throw switches. All of the switches 141 and 144 are inter-connected by wiring which is energized from a suitable source of electric current. In order to simplify the wiring diagram, the points indicated by the black dots 157 to 166 inclusive are assumed to be interconnected and in turn to be connected to a source of electric current.

Operation

In the operation of the invention, let it be assumed that the various parts of the machine are in the position shown in Figures 1 and 4. Let it also be assumed that a supply of bushings 22

to be sized has been placed in the chute 23, as shown in Figures 1 and 3, with the lower-most bushing 22 supported upon the rest 28. The manual switch 140 is now closed by the operator, energizing the forward solenoid coil 127 of the four-way valve 88 by way of the left-hand contacts of the limit switch 144, which at this time are bridged by the switch bar. This action shifts the four-way valve 88 to its forward stroke position, so as to admit pressure fluid from the line 117 to the line 111 and port 44 at the left-hand end of the cylinder bore 33. This pressure fluid pushes the plunger head 35, rod 34 and annular abutment 40 to the right until the annular abutment surface 42 engages the left-hand end of the die 17. The fluid escaping from the right-hand end of the cylinder 32 escapes through the port 43, conduit 110, valve 88 and conduit 122 back to the tank 119. The parts have now reached the positions shown in Figure 5. Meanwhile, the switch bar of the limit switch 141 has rolled off the projection 149 as the arm 150 has moved to the right, opening its contacts and de-energizing the switch 141.

When the annular abutment 40 has reached the end of its travel, the end 152 of the arm 150 trips the limit switch 142, closing its contacts and thereby energizing the solenoid 131 of the four-way valve 89. This causes pressure fluid to flow from the conduit 117 into the conduit 112 and port 51 into the space immediately adjacent the cylinder head 53 of the cylinder 48. This pressure forces the outer plunger 50 to the left, causing the outer sizing plunger 63 to engage the lowermost bushing 22 and push it into the bore 18 of the sizing die 17. Meanwhile, the fluid escaping from the forward end of the cylinder bore 49 returns to the tank 119 by way of the port 52, conduit 113, valve 89 and conduit 112. The parts have now reached the positions shown in Figure 6.

As the outer sizing plunger 63 reaches the end of its travel, the projection 153 on the arm 155 trips the limit switch 143, unbridging its left-hand contacts and bridging its right-hand contacts. The former de-energizes the solenoid winding 131 of the four-way valve 89, so that its spool returns to its neutral position and holds the plunger 63 in its attained position. The tripping of the limit switch 143 is accompanied by the unbridging of the left-hand contacts and the bridging of the right-hand contacts of the limit switch 144 as the end 154 of the arm 155 travels leftward.

The bridging of the right-hand contacts of the limit switch 144 energizes the solenoid winding 135 of the four-way valve 90, shifting it to forward stroke. Pressure fluid is then delivered through the conduit 115 to the right hand end 60 of the cylinder bore 77, shifting the plunger head 76 and inner sizing plunger 68 to the left, causing the latter to enter the bore of the bushing 22. Meanwhile, the fluid displaced from the left-hand side of the head 76 escapes back to the tank 119 by way of the stem 80, conduit 114, valve 90 and conduit 122. The parts have now reached the positions shown in Figure 7.

With the various plungers halted in engagement with the bushing 22, the pump 116 continues to deliver pressure fluid thereto and the pressure rises in the hydraulic circuit until it closes the normally open pressure switch 124. This energizes the return solenoid winding 126 of the four-way valve 88, shifting it upon return stroke and causing the flow of pressure fluid to

the cylinder bore 33 to be reversed, thereby reTRACTING the abutment plunger 34. At the same time the closing of the pressure switch 124 also bridges its left-hand pair of contacts so as to re-energize the forward solenoid winding 131 of the four-way switch 89, shifting this to forward stroke. This delivers pressure fluid through the conduit 112 to cause the plunger head 65 and plunger rods 59 and 63 to move to the left, expelling the bushing 22 from the sizing die 17 as the abutment plunger 34 is retracted. The parts have now reached the positions shown in Figure 8.

As the abutment plunger 34 is retracted to the position shown in Figure 1, the projection 149 on the arm 150 closes the normally-open limit switch 141, thereby energizing the return solenoid windings 130 and 134 of the four-way valves 89 and 90, shifting these valves to return stroke positions. This causes pressure fluid to be delivered through the conduits 113 and 114, retracting the outer and inner plungers 59 and 74 and also the sizing plungers 63 and 68. The parts have now reached the positions shown in Figure 9, and the bushing, thus ejected by the retraction of the plungers 63 and 68, drops into a suitable receiver. Meanwhile, another bushing 22 drops from the chute 23 onto the rest 28.

The retraction of the plunger 59 causes the end 154 of the arm 155 to trip the limit switch 144 so as to unbridge its right-hand contacts and bridge its left-hand contacts, as shown in Figure 1. This de-energizes the return solenoid windings 130 and 134 of the four-way valves 89 and 90, shifting them to their neutral positions and halting the retraction of the plungers 59 and 74. The bridging of the left-hand contacts of the limit switch 144, however, starts the cycle of operations anew by re-energizing the forward solenoid winding 127 of the four-way valve 89, shifting it to forward stroke position. Assuming that the manual switch 140 is still closed, the above described cycle of operations repeats itself indefinitely as long as bushings 22 are supplied to the chute 23 to be sized.

What I claim is:

1. In combination in a bushing sizing apparatus, an external bushing sizing member having a sizing bore therein open at both ends with its internal diameter slightly smaller than the external diameter of the bushing to be sized for receiving said bushing, a movable abutment member engageable with one end of said external sizing member, a bushing feeding member of smaller diameter than said bore engageable with one end of said bushing to feed said bushing into said sizing bore, an internal bushing sizing member of the internal diameter desired for said bushing, engageable with the interior of said bushing, fluid pressure motors connected to said abutment member and to said feeding member and to said internal sizing member, a source of pressure fluid connected to said motors, a fluid pressure control circuit including a conduit system connecting said motors to said fluid pressure source and containing control valves operable in timed relationship to move said abutment member into engagement with one end of said sizing member and to move said feeding member toward the other end of said external sizing member to feed said bushing into said bore, and to move said internal sizing member into said bushing and thereafter to retract said abutment member and to further advance said pressure-responsive device operable to retract said abutment member and to further advance said feeding member through said bore to eject said bushing from said bore.

4. In combination in a bushing sizing apparatus, a sizing die having a sizing bore therein open at both ends with its internal diameter slightly smaller than the external diameter of the bushing to be sized for receiving said bushing, a fluid-pressure-operated abutment plunger movable into engagement with one end of said die, a fluid-pressure-operated feeding plunger of smaller diameter than said bore engageable with said feeding member through said bore to eject

said bushing from said bore in response to the attainment of a predetermined pressure in said circuit.

2. In combination in a bushing sizing apparatus, an external bushing sizing member having a sizing bore therein open at both ends with its internal diameter slightly smaller than the external diameter of the bushing to be sized for receiving said bushing, a movable abutment member engageable with one end of said external sizing member, a bushing feeding member of smaller diameter than said bore engageable with one end of said bushing to feed said bushing into said sizing bore, an internal bushing sizing member of the internal diameter desired for said bushing engageable with the interior of said bushing, fluid pressure motors connected to said abutment member and to said feeding member and to said internal sizing member, a source of pressure fluid connected to said motors, a fluid pressure control circuit including a conduit system connecting said motors to said fluid pressure source and containing control valves operable in timed relationship to move said abutment member into engagement with one end of said sizing member and to move said feeding member toward the other end of said external sizing member to feeding said bushing into said bore, and to move said internal sizing member into said bushing and a pressure-responsive device operable to retract said abutment member and to further advance said feeding member through said bore to eject said bushing from said bore and withdraw said internal sizing member from said bushing in response to the attainment of a predetermined pressure in said circuit.

3. In combination in a bushing sizing apparatus, an external bushing sizing member having a sizing bore therein open at both ends with its internal diameter slightly smaller than the external diameter of the bushing to be sized for receiving said bushing, a movable abutment member engageable with one end of said external sizing member, a bushing feeding member of smaller diameter than said bore engageable with one end of said bushing to feed said bushing into said sizing bore, an internal bushing sizing member of the internal diameter desired for said bushing engageable with the interior of said bushing, fluid pressure motors connected to said abutment member and to said feeding member and to said internal sizing member, a source of pressure fluid connected to said motors, and a fluid pressure control circuit including a conduit system connecting said motors to said fluid pressure source and containing control valves operable in timed relationship to move said abutment member into engagement with one end of said sizing member and to move said feeding member toward the other end of said external sizing member to feed said bushing into said bore, and to move said internal sizing member into said bushing and thereafter to retract said abutment member and to further advance said feeding member through said bore to eject said bushing from said bore.

7. In combination in a bushing sizing apparatus, a sizing die having a sizing bore therein open at both ends with its internal diameter slightly smaller than the external diameter of the bushing to be sized for receiving said bushing, a fluid-pressure-operated abutment plunger movable into engagement with one end of said die, a fluid-pressure-operated feeding plunger of smaller diameter than said bore engageable with

one end of said bushing to feed said bushing into said bore, a fluid-pressure-operated internal sizing plunger of the internal diameter desired for said bushing movable into the interior of said bushing, a source of pressure fluid, a fluid pressure circuit connecting said source of pressure fluid to said plungers, a fluid pressure control circuit including a conduit system connecting said motors to said fluid pressure source and containing control valves operable in timed relationship to move said abutment plunger into engagement with one end of said die and also to move said feeding plunger toward said die to feed said bushing into said bore and finally to move said internal sizing plunger into said bushing and a pressure responsive device operable in response to the attainment of a predetermined pressure in said fluid pressure circuit to retract said abutment plunger and to further advance said feeding plunger through said bore to eject said bushing from said bore.

5. In combination in a bushing sizing apparatus, a sizing die having a sizing bore therein open at both ends with its internal diameter slightly smaller than the external diameter of the bushing to be sized for receiving said bushing, a fluid-pressure-operated abutment plunger movable into engagement with one end of said die, a fluid-pressure-operated feeding plunger of smaller diameter than said bore engageable with one end of said bushing to feed said bushing into said bore, a fluid-pressure-operated internal sizing plunger of the internal diameter desired for said bushing movable into the interior of said bushing, a source of pressure fluid, a fluid pressure circuit including a conduit system connecting said source of pressure fluid to said plungers, a pressure fluid control valve in said conduit system connected between said source and each of said plungers, an electrical valve operator connected to each valve, and an electrical control circuit interconnecting said operators, said electrical control circuit including a pressure responsive switch operable in response to the attainment of a predetermined pressure in said fluid pressure circuit to energize certain of said operators to retract said abutment plunger and to further advance said feeding plunger through said bore to eject said bushing from said die.

6. A bushing sizing press comprising a supporting structure, a die holder mounted on said structure, an external bushing sizing die mounted on said die holder and having a bore therethrough open at both ends with its internal diameter slightly smaller than the external diameter of the bushing to be sized and adapted to receive said bushing, a plurality of fluid pressure motors mounted on said structure on opposite sides of said die holder, an annular abutment member mounted on one motor and having a bushing feeding member receiving socket, said abutment member being disposed in alignment with said die and movable into and out of closing engagement with one end of said bore, a bushing feeding member of smaller diameter than said bore mounted on one motor and movable through said

bore from the opposite end thereof and an internal bushing sizing member of the internal diameter desired for said bushing mounted upon one motor and movable into and out of said bushing.

7. A bushing sizing press comprising a supporting structure, a die holder mounted on said structure, an external bushing sizing die mounted on said die holder and having a bore therethrough open at both ends with its internal diameter slightly smaller than the external diameter of the bushing to be sized and adapted to receive said bushing, a plurality of fluid pressure motors mounted on said structure on opposite sides of said die holder, an annular abutment member mounted on one motor and having a bushing feeding member receiving socket, said abutment member being disposed in alignment with said die and movable into and out of closing engagement with one end of said bore, a bushing feeding member of smaller diameter than said bore mounted on one motor and movable through said bore from the opposite end thereof, an internal bushing sizing member of the internal diameter desired for said bushing mounted upon one motor and movable into and out of said bushing and a bushing holder adapted to contain a multiplicity of bushings and having a bushing rest at its outlet mounted adjacent said die and positioned to hold a bushing in alignment with said bore and said feeding member.

8. A bushing sizing press comprising a supporting structure, a die holder mounted on said structure, an external bushing sizing die mounted on said die holder and having a sizing bore therethrough open at both ends with its internal diameter slightly smaller than the external diameter of the bushing to be sized and adapted to receive said bushing, a fluid-pressure-operated annular abutment plunger having a sizing plunger receiving socket therein, said abutment plunger being movable into and out of engagement with one end of said die, and telescoping feeding and internal sizing plungers movable toward and away from said die and into engagement with said bushing to push said bushing into said die and insert said sizing plunger in said bushing, said feeding plunger having an external diameter smaller than the minimum internal diameter of said sizing bore.
